UNITED STATES PATENT OFFICE.

SETH WILLIAM BABBITT, OF MERIDEN, CONNECTICUT.

DESIGN FOR A BOX.

SPECIFICATION forming part of Design No. 22,986, dated December 26, 1893.

Application filed November 14, 1893. Serial No. 490,963. Term of patent 3½ years.

To all whom it may concern:

Be it known that I, SETH WILLIAM BABBITT, a citizen of the United States, residing at Meriden, in the county of New Haven and 5 State of Connecticut, have invented a certain new and original Design for Boxes, of which the following is a description, reference being had to the accompanying drawings.

This invention relates to a new and original 10 design for "boxes," more especially that class of boxes used for the reception of trinkets, pins, hair pins, and articles of jewelry.

The design is illustrated in the accompanying 15 drawings, wherein—

Figure 1 is a perspective view of a box embodying the design, and Fig. 2 is a top plan view.

The design of the "box" consists in the 20 representation of two hearts arranged longitudinally with their ends or apexes overlapping at the center. The space on the opposite sides of the center is occupied by fanciful designs. On the upper face of one of the heart-

shaped representations is the representation of a hair pin, its prongs being represented as 25 passing through the apex of the opposite heart and its ends resting on the upper face beyond the apex. Surrounding the box is a flange having a beaded upper face. The base has suitable feet or legs thereon as shown.

The essential feature of the design is the 30 box having its top or upper portion shaped to represent two hearts arranged longitudinally and surrounded by a fanciful border.

Having thus described the invention, what 35 is claimed as new, and desired to be secured by Letters Patent, is—

The design for a box substantially as shown and described.

In testimony whereof I affix my signature in 40 presence of two witnesses.

SETH WILLIAM BABBITT.
